N. STARKS,

Bolt-Heading Machine,

No. 8,616.

Patented Dec. 23, 1851.

UNITED STATES PATENT OFFICE.

NATHAN STARKS, OF ALBANY, NEW YORK.

BOLT-HEADING MACHINE.

Specification of Letters Patent No. 8,616, dated December 23, 1851.

To all whom it may concern:

Be it known that I, NATHAN STARKS, of the city and county of Albany and State of New York, have invented certain new and useful Improvements in Machinery for Heading Bolts; and I do hereby declare that the following is a full, clear, and exact description of my said invention, reference being had to the accompanying drawing, which forms part of this specification, and in which—

Fig. 1 represents a front elevation of my bolt header; Fig. 2 is a side elevation thereof; and Fig. 3 is a plan of the same.

15 The machine represented in the accompanying drawing is arranged to form square heads upon bolts; it consists mainly of a strong frame to support the various moving parts of the machine, of a set of gripping dies to grip the neck of the bolt blank on which a head is to be formed, of the punch and its stock for thickening or upsetting the extremity of the bolt blank, of the shaping dies for giving form to the 20 thickened extremity of the bolt blank, and of the mechanism by which the punch and dies are operated.

The frame A is constructed of cast iron and is supported by legs b, which raise it sufficiently from the floor to enable the operator to work conveniently. The gripping dies, C C, are situated at the front extremity of the frame, and are two in number; their adjacent faces have grooves formed in them to fit the opposite sides of the bolt blank, which may be either round or of any other form which may be required. These gripping dies are secured to the upper extremities of a pair of swinging die stocks, d d, which extend downward through transverse slots in the frame and are pivoted at their lower extremities to a block E secured to the lower part of the frame. These die stocks serve to steady and guide the gripping dies, which are caused to diverge from each other by springs, f f, which act upon the inner faces of the die stocks. The gripping dies are forced toward each other by means of toggle jointed levers which are moved by the foot of the operator; in order to accomplish this each pair of toggle jointed levers, g g, is connected at its point by means of a rod h with the extremity of a cross bar I beneath; and the latter is connected at its middle by means of a link j

with a treadle K to which the foot of the operator is applied.

The punch stock L is situated behind the gripping dies and is arranged to slide in suitable guides, m m, endwise and horizontally toward and from the gripping dies, in the line of the axis of the opening or grooves therein. The hinder extremity of this punch stock is connected by a rod n with the wrist of a crank shaft, O, that is supported in suitable pillow blocks at the hinder extremity of the frame A, and to which a rotary motion is imparted by some convenient prime mover. In the present instance the crank shaft is fitted with a winch to be turned by manual labor, and a fly wheel p is secured to it to equalize the motion. The front extremity of the punch stock is fitted with the punch, which by the movement of the stock is alternately forced 70 toward the hinder faces of the gripping dies and withdrawn therefrom. When nearest the gripping dies the distance between its face and their adjacent faces equals the thickness of the bolt head to be formed; and when farthest therefrom, this distance is sufficient to receive that portion of the bolt blank which is to be upset to form the head. Immediately behind the gripping dies is the frame R in which the shaping dies are 80 supported.

As the present machine is designed to form square bolt heads, the dies, s, s, s, s, are square faced; they are four in number and are arranged to slide toward and from each other in seats formed in the frame R; when nearest together the space included between their faces is of the exact form of the head to be made. Each shaping die is slotted to admit the front arm of a lever T, which is pivoted to a strong frame U secured to the bed frame, and whose hinder arm extends backward in a direction parallel with that of the punch stock L. The hinder extremity of each lever is rounded and is borne against the adjacent face of the punch stock by a spring v, which by forcing the hinder arm of the lever inward turns the forward arm thereof outward, and thus moves outward the shaping die upon which the lever acts. The hinder extremities of the four levers bear upon the adjacent faces of the punch stock which is swelled at this point in the form of a pyramid w whose base is toward the dies; 110

hence as the punch stock is drawn backward, or caused to retrograde, the inclined faces of this swelled portion acting upon corresponding extremities of the levers cause them to diverge, thus turning their front extremities inward and forcing the shaping dies toward each other; while on the other hand, as the punch stock is forced forward the inclined faces permit the hinder arms 10 of the levers to be moved inward by the springs, which thus turn the levers upon their pivots and cause the shaping dies to diverge.

When the machine is in operation both 15 planks are entered one at a time between the open gripping dies at the time the punch is retrograding under the action of the crank shaft. As the punch reaches the extremity of its retrograde stroke the operator de- 20 presses the treadle with his foot and thus causes the gripping dies to converge and grip the neck of the bolt blank. As then the punch stock is moved forward by the continued revolution of the crank shaft, that 25 portion of the bolt blank extending between the hinder faces of the gripping dies and the face of the punch is compressed or upset and is thus thickened, while as the punch retrogrades the shaping dies are forced 30 against the sides of this thickened portion to flatten them and thus give the head its proper shape. The operator then releases the pressure upon the treadle, thus permitting the springs *f f* to open the gripping 35 dies, and withdraws the headed bolt.

The machine represented in the accompanying drawing is designed for shop work and to be operated by manual labor; the gripping dies are therefore arranged to be 40 operated by the foot of the operator, as this arrangement permits him to maintain the bolt blank in place during several revolutions of the crank shaft whereby the formation of a perfect head is insured. In ma- 45 chines to be driven by power I intend to actuate the gripping dies at the proper moments to grip and unloose the bolt by

means of a cam secured to the crank shaft, which may be made to act upon the toggle jointed levers through the intervention of 50 levers and rods or other suitable mechanism.

The machine described is arranged as above mentioned to form square heads upon bolts and consequently the shaping dies 55 and punch are square faced, but bolt heads of any required form may be made in the same machine by applying to it a punch and dies whose faces are the counterparts of the head to be produced. In large machines 60 the power may be transmitted to the crank shaft through the intervention of gearing; the shaping dies may also be caused to diverge by the action of a pyramidal swell upon the forward extremity of the punch 65 stock acting upon the forward ends of the levers in place of the springs which in the machine described act upon the hinder ends of the levers; in this case the base of this secondary swelled portion of the punch 70 stock will face the base of the first swelled portion the two thus acting alternately and antagonistically upon the levers and the shaping dies.

Having thus described my improved ma- 75 chine for heading bolts what I claim therein as new and desire to secure by Letters Patent, is—

The combination of the upsetting punch, the dies for shaping the sides of the head, 80 the levers for working the dies and the protuberance on the punch stock for actuating the levers so that by the forward movement of the punch stock, the punch is caused to upset the end of the bolt, and by 85 its retrograde movement the dies are worked which give shape to the sides of the head as herein set forth.

In testimony whereof I have hereunto subscribed my name.

NATHAN STARKS.
